UNITED STATES PATENT OFFICE

2,471,765

CHICK FOUNTAIN GUARD

John R. Morton, Mountain Grove, Mo.

Application November 19, 1946, Serial No. 710,739

4 Claims. (Cl. 119—72)

1

This invention relates to guard devices, and more particularly to a guard device to protect a drinking pan or fountain for chicks from becoming fouled or contaminated from chick droppings, and the like.

A main object of the invention is to provide a novel and improved fountain guard device for chick fountains which is very simple in construction; easy to install, and very effective in protecting a chick drinking pan or fountain.

A further object of the invention is to provide an improved guard device for chick fountains which may be fabricated from inexpensive materials and which comprises only a few simple parts.

Further objects and advantages of the invention will become apparent from the following description and claims, and from the accompanying drawings, wherein:

Figure 1 is a top plan view of a fountain guard device constructed in accordance with the present invention.

Figure 2 is a side elevational view of the guard device of Figure 1, the pan being shown in cross-section.

Figure 3 is an enlarged cross-sectional detail view taken on line 3—3 of Figure 1.

Figure 4 is a detail sectional view on the section line 4—4 of Figure 1 showing the attachment of the arched vertical band to the radially positioned strip members.

Figure 5 is a detail sectional view on the section line 5—5 of Figure 1 showing the same feature.

Referring to the drawings, 11 designates a generally circular band of rigid material, such as steel strip or the like, suitably galvanized or otherwise protected against corrosion, which forms the base of the guard device. Connected to band 11 at diametrically opposed points by bolts 12 and 13 is an arched vertical band 14 formed at its crest with a downwardly facing channel portion 15. Connected to band 11 at a location approximately 90 degrees arcuately spaced from the bolts 12 and 13 is an upwardly and inwardly curved strip member 16 secured to band 11 by a bolt 17. The top end of strip member 16 is formed with a vertical arm 18 adapted to abut the edge of channel portion 15. A similar strip member 19 is connected to band 11 diametrically opposite bolt 17 by a bolt 20. The top end of strip member 19 is formed with a vertical arm 21 adapted to abut the edge of channel portion 15 opposite to arm 18. A bolt 22 passes through arm 18, channel portion 15 and arm 21 to rigidly unite strip members 16 and 19 to arched band 14 at its crest.

Secured to band 11 by bolts 17 and 20 are the

ends of a pair of symmetrically positioned inclined guard strips 23 and 24 which respectively contact the under surfaces of the opposed arms of arched band 14 at their intermediate regions and are preferably secured thereto as at 14' and 14'' respectively by welding, soldering, or other suitable fastening means. Guard strips 23 and 24 overlie the central region of the area defined by band 11 and cooperate with strip members 16 and 19 to protect said central region against being fouled by chick droppings.

In use, the guard device is positioned in a drinking pan or fountain 25 in the position shown in Figure 2. The crest portion of the guard device 15 has the upwardly projecting top ends of arms 18 and 21 which form prongs 30 and 31 respectively. Said prongs discourage chicks from roosting on the crest of the guard. The side portions of strip members 14, 16 and 19 are rather steeply inclined so that roosting thereon by the chicks is also difficult. Access to the pan 25 however is substantially permitted for drinking, since adequate clearance is provided at the side portions of the guard adjacent the ends of the arched strip member 14.

The guard device prevents chicks from standing in the pan or fountain 25 and from roosting directly over said pan or fountain. This prevents fouling of the drinking water by the chicks and maintains substantially sanitary conditions in the immediate area around the pan. The guard device is readily removable for filling the pan.

While a specific embodiment of a guard device for chick drinking fountains or water pans has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A guard device for drinking pans comprising a generally circular rigid base member, a plurality of rigid strip elements secured to said base member at equal arcuate points along the periphery of the latter member, said elements extending upwardly and toward a point above the center of said base member, means securing together the portions of said strip elements adjacent the point above the center of said base member, and a plurality of inclined arcuate strips secured to said base member and secured to the intermediate portions of certain of the rigid strip elements.
2. A guard device for drinking pans, comprising

a generally circular rigid base member, a plurality of rigid strip elements secured to said base member at equal arcuate points along the periphery of the latter member, said elements extending upwardly and toward a point above the center of said base member, two of said strip elements being substantially diametrically-opposed and formed at the portion adjacent the point above the center of said base member with vertical prong portions, a third strip element having a channel portion at its top, and attachment means extending through said vertical prong portions and said channel portion.

3. A guard device for drinking pans comprising a generally circular rigid base member, two rigid strip elements arranged in end-to-end relation and having the ends remote from each other secured to said base member at diametrically-opposed points along the periphery of the latter member, said strip elements extending upwardly and toward a point above the center of said base member, the other adjacent ends of said strip elements being each provided with vertical prong portions, a third arched rigid strip element secured at its ends to the periphery of said base member mid-way between the secured ends of the first two rigid strip elements and also extending from its secured ends upwardly and toward the point above the center of said base member, said third rigid strip element being formed at the crest of its arch with a transverse channel portion positioned intermediate the vertical prong portions, and attachment means projecting through the vertical prong portions and the said channel portion.

4. A guard device for drinking pans comprising a generally circular rigid base member, two rigid strip elements arranged in end-to-end relation and having the ends remote from each other secured to said base member at diametrically-opposed points along the periphery of the latter member, said strip elements extending upwardly and toward a point above the center of said base member, the other adjacent ends of said strip elements being each provided with vertical prong portions, a third arched rigid strip element secured at its ends to the periphery of said base member mid-way between the secured ends of the first two rigid strip elements, said third arched strip element having at the crest of its arch a transverse channel portion positioned intermediate the vertical prong portions, attachment means projecting through the vertical prong portions and the said channel portion, and a pair of inclined arcuate strip elements secured to said base member at diametrically opposed points, each of said latter inclined arcuate strip elements abutting and being secured to an intermediate portion of the third arched strip element.

25 JOHN R. MORTON.
